GREETING CARD

Dolores Adams, Nashville, Tenn.

Application September 13, 1951, Serial No. 16,627

Term of patent 7 years

(Cl. D59—2)

To all whom it may concern:

Be it known that I, Dolores Adams, a citizen of the United States of America, residing at Nashville, in the county of Davidson and State of Tennessee, have invented a new, original, and ornamental Design for a Greeting Card, of which the following is a specification, reference being had to the accompanying drawing, forming a part hereof, wherein the single figure of the drawing is a perspective view of a greeting card, illustrating my new design. The back of the greeting card is unornamented.

The essential features of my design are shown in full lines.

I claim:

The ornamental design for a greeting card, as shown and described.

DOLORES ADAMS.
